[57] CLAIM

The ornamental design for a digital calendar watch, as shown and described.

DESCRIPTION

FIG. 1 is a top perspective view of a digital calendar watch showing my new design;
FIG. 2 is a right side elevation view thereof;
FIG. 3 is a bottom plan view thereof; and
FIG. 4 is a top perspective view of another embodiment of my new design of FIG. 1 wherein the calendar and time indicator windows have been inverted, the appearance of the right and bottom sides thereof being the same as in FIGS. 2 and 3 respectively with the day-changing crown inverted.
